METAL SHELVING AND METHOD OF MAKING THE SAME

Robert T. Stophlet, Toledo, Ohio, assignor to The Toledo Porcelain Enamel Products Company, Toledo, Ohio, a corporation of Ohio

Application March 26, 1935, Serial No. 13,094

5 Claims. (Cl. 113—116)

This invention relates to metal shelving and its principal object is the provision of a light, rigid shelf that is attractive in appearance, economical to manufacture and which will withstand high temperatures so that it can be vitreous porcelain enameled without becoming distorted.

Other objects and advantages will be apparent from the following description, in which reference is had to the accompanying drawings illustrating a preferred embodiment of my invention and wherein similar reference numerals designate similar parts throughout the several views.

In the drawings:—

Figure I is a view in perspective of a shelf constructed in accordance with my invention.

Figure II is an enlarged plan view of a flat blank from which the shelf shown in Figure I is formed, the central part of the blank being broken away.

Figure III is a view in perspective showing the blank after the first forming operation; and

Figure IV is an enlarged end elevational view of the shelf illustrated in Figure I.

Referring to the drawings in detail, the shelf 1 of my invention, though light in weight, is stiffened so that it is capable of supporting heavy loads without sagging, the stiffening means consisting of a bead or groove 2 extending longitudinally of the shelf intermediate its sides, marginal beads 3 and 4 extending along the sides of the shelf and flanges 5 and 6 depending from the marginal beads 3 and 4. Since either the flange 5 or the flange 6 may form the front of the shelf, the edges of the flanges are turned under, as at 7 and 8, to enhance the appearance, and the flanges are perforated, as at 9, 10 and 11, to facilitate fastening of price tags thereto.

Additional stiffness may be attained when desired by providing two or more beads instead of the single bead 2.

The corners of the blank from which the shelf is formed are cut out, as at 12, 13, 14 and 15, and the ends of the blank are bent downwardly to form end flanges 16 and 17 suitable for attachment to uprights (not shown). In order to avoid crowding the metal along the stiffening bead 2, and thus setting up strains which cause the shelf to warp under the influence of high temperatures to which it is necessarily subjected when a coating of vitreous porcelain enamel is fused upon it, openings 18 and 19 are cut into the blank where the junctions of the end flanges 16 and 17 with the body of the shelf will intersect the stiffening bead 2.

In manufacturing the shelf, the blank is first

cut into the shape illustrated in Figure II and provided with perforations such as 9, 11, etc., and with the openings 18 and 19. If desired, the blank may be cut to shape and the perforations and openings punched by means of blanking dies in one operation. The stiffening bead 2 is preferably stamped or rolled into the blank after it is cut and punched, the blank thus assuming the form illustrated in Figure III. The marginal beads 3 and 4 may be formed and the side flanges 5 and 6 and end flanges 16 and 17 bent down in separate operations, but where the quantities to be manufactured are large, the marginal beads 3 and 4 may be formed and the side and end flanges bent down by means of forming dies in the same operation, the edges of the side flanges being subsequently turned under as at 7 and 8. The stiffening bead 2 will project downwardly, as illustrated in the drawings, or upwardly, depending upon the direction in which the side and end flanges are bent, but the shelf is preferably so formed that the stiffening bead 2 will project downwardly so as not to engage articles placed upon the shelf. It is possible to bend downwardly the end flanges 16 and 17 of blanks not provided with openings such as 18 and 19, but because of strains set up in the metal of blanks not provided with such openings, warpage is liable to occur when the blanks are subjected to the temperatures required to fuse coatings of vitreous porcelain enamel upon them.

The embodiment of my invention shown and described is to be regarded as illustrative only, and it is to be understood that the invention is susceptible to variation, modification and change within the spirit and scope of the subjoined claims.

Having described my invention, I claim:—

1. A sheet metal shelf having down-turned flanges at its ends and a longitudinally extending bead intersecting the corners formed at the junctions of said flanges with the body of the shelf, said bead being completely interrupted by openings through the metal of the shelf at the intersections of said bead and said flanges, and a coating of vitreous enamel fused upon the body of the shelf.

2. The method of making a shelf which includes the steps of cutting a flat blank of sheet metal having openings therethrough adjacent its ends, forming a stiffening bead in said blank, said bead extending across and being completely interrupted by said openings, and bending the ends of said blank to form flanges extending in planes substantially perpendicular to the

plane of said blank and intersecting the plane of said blank along lines lying across said openings.

3. The method of making a porcelain enameled sheet metal shelf which includes the steps of cutting a flat blank of sheet metal having openings therethrough adjacent its ends, forming a stiffening bead in said blank extending across and being completely interrupted by said openings, bending the ends of said blank to form flanges extending in planes substantially perpendicular to the plane of said blank and intersecting the plane of said blank along lines lying across said openings, and fusing a coating of vitreous enamel upon the structure so formed.

4. The method of making a porcelain enameled sheet metal shelf which includes the steps of cutting a flat blank of sheet metal having openings therethrough adjacent its ends, forming a stiffening bead in said blank extending across and being completely interrupted by said openings, bending the ends of said blank to form flanges extending in planes substantially perpendicular to the plane of said blank and intersecting the plane of said blank along lines lying across said openings, forming marginal

beads extending parallel to the sides of said blank, bending the side portions of said blank into planes perpendicular to the plane of the body of said blank, and fusing a coating of vitreous enamel upon the structure so formed. 5

5. The method of making a porcelain enameled sheet metal shelf which includes the steps of cutting a flat blank of sheet metal having openings therethrough adjacent its ends, forming a stiffening bead in said blank extending 10 across and being completely interrupted by said openings, bending the ends of said blank to form flanges extending in planes substantially perpendicular to the plane of said blank and intersecting the plane of said blank along lines 15 lying across said openings, forming marginal beads extending parallel to the sides of said blank, bending the side portions of said blank into planes perpendicular to the plane of the body of said blank, bending the edges of said 20 side portions inwardly into planes substantially parallel to the plane of the body of said blank, and fusing a coating of vitreous enamel upon the structure so formed.
